Primary Examiner—Prabhakar Deshmukh*Assistant Examiner*—Derrick Holland(74) *Attorney, Agent, or Firm*—Jenkins, Wilson, Taylor & Hunt, P.A.(57) **CLAIM**

The ornamental design for a facial stimulation apparatus, as shown and described.

DESCRIPTION

FIG. 1 is a perspective view of a facial stimulation apparatus according to the present invention;

FIG. 2 is a front view of a facial stimulation apparatus according to the present invention;

FIG. 3 is a rear view of a facial stimulation apparatus according to the present invention;

FIG. 4 is a left side of a facial stimulation apparatus according to the present invention;

FIG. 5 is a top view of a facial stimulation apparatus according to the present invention and wherein the right end view is an inverted mirror image of the left end view;

FIG. 6 is a bottom view of a facial stimulation apparatus according to the present invention; and,

FIG. 7 is a right side view of a facial stimulation apparatus according to the present invention.

The broken lines shown represent unclaimed subject matter and form no part of the claimed design.
